TREE SUPPORT

Hiram M. Maxwell, 12631 Imperial Highway,
Santa Fe Springs, Calif. 90670

Filed June 2, 1969, Ser. No. 17,432

Term of patent 14 years

Int. Cl. D31

U.S. Cl. D35—1

FIG. 1 is a perspective view of a tree support showing my new design;

FIG. 2 is a top plan view of said tree support;

FIG. 3 is an end elevational view thereof taken as indicated by the arrow 3 in FIG. 1; and

FIG. 4 is a rear elevational view taken as indicated by the arrow 4 in FIG. 1.

I claim:

The ornamental design for a tree support, substantially as shown and described.
